UNITED STATES PATENT OFFICE.

ROBERT REID, OF PHILADELPHIA, PENNSYLVANIA.

HOISTING-MACHINE.

SPECIFICATION forming part of Letters Patent No. 278,821, dated June 5, 1883.

Application filed February 5, 1883. (No model.)

To all whom it may concern:

Be it known that I, ROBERT REID, of the city of Philadelphia, county of Philadelphia, and State of Pennsylvania, have invented an Improvement in Hoisting-Machines, of which the following is a specification.

My invention has reference to hoisting-machines in general, but more particularly to that class of such devices which are technically known as "portable hoisting-machines," and it consists in gearing, combined with lifting and hand chain wheels and bearings of peculiar construction, whereby the machine is prevented from running down, and in many details of construction, all of which are fully set forth in the following specification, and shown in the accompanying drawings, which form part thereof.

Heretofore it has been customary to rotate the lifting-chain wheel by means of a worm and worm-wheel. The bearing-surface between the two being small, the wear is great, the speed is slow, and the worm should run in oil. By my construction the cost is greatly lessened, as the worm-wheel is dispensed with, the gearing may run comparatively dry, will not run down, and the friction necessary to prevent said running down is automatically increased or decreased with the varying weights of the different loads supported. Greater simplicity is attained, and the device as a whole is not as liable to get out of order or wear out so soon as those in which the worm is used.

In the drawings, Figure 1 is a side elevation of my improved hoisting-machine. Fig. 2 is an end elevation of same, with part in section. Fig. 3 is a side elevation of the lifting-chain guide to keep the chain in the groove in the chain-wheel; and Fig. 4 is a plan view of the hand-chain guide, which is adapted to keep the endless hand-chain in the groove of the chain-wheel over which it runs.

A A are frame-plates secured together at the bottom by stay E, in the middle by shaft B, upon which the lifting-chain wheel C is journaled, and are provided at the top with bearing eyes or holes A'.

The chain-wheel C may be made in any desired manner, but I prefer it to have the chain-groove between two spur-wheels, D D, cast integral therewith or otherwise secured thereto.

H is the supporting-hook, and is pivoted to

the stay or cross bar G, bolted at each end to the eye or bearing-pieces F, which are provided with bearing eyes or holes F', similar to A'. 55 These plates F and A are hinged together by the journals I, having flanges i on their inner sides, as shown.

Secured to these journals is the shaft J of the pinion K, which latter is located between 60 the journals I and meshes with the spur-wheels D. The outer end of the shaft J is secured to the hand-chain wheel L, over which the chain R travels, and is prevented from getting off said wheel by guide N, which fits the flange of 65 said chain-wheel L, and is supported and carried by an extension, f, to one of the plates F.

It is evident that the journals I and shaft J may be made solid, or these may be made integral with the pinion K. The lifting-chain 70 P passes over the chain-wheel C, and is prevented from becoming displaced by the curved guide M, having groove M' to receive the line of metal formed by the extending links, and an eye or bearing, m, which encircles the pinion K or its shaft and is prevented from lateral displacement by the spur-wheels D. 75

The operation is as follows: The load being attached to the chain P, the frame A and chain-wheel C will naturally swing to one side, as 80 indicated in Fig. 1, except that in practice the chain P would never pass a vertical line through the supporting-hook H or shaft J. The plates A being hinged to plates F, the friction due to the support of the load comes 85 upon the large journals I, and which is sufficient to prevent the running down of the machine with the heaviest load it is adapted to support. As the load varies in weight the frame-carrying chain-wheel C varies from a vertical 90 position to an angular one, its pivotal point being at J, and the amount of friction also varies. In the same ratio the power necessary to be exerted to raise or lower the load is proportional to the same. Somewhat the same effect would be attained if the frame-plates A and 95 F were made integral; but I prefer hinging them, as shown. By this construction of hoist great speed in raising or lowering loads is attained, as it is possible to vary the ratio between 100 the spur-wheels D and pinion K within large limits; or, if desired, intermediate gearing may be used to increase the speed.

I do not limit myself to the construction

shown, as it may be modified in various ways without departing from my invention—as, for instance, by providing additional means to rotate the lifting-chain wheel and independent of the friction-bearings designed to prevent the machine running down, and any suitable devices may be used by which to bring the weight of the load upon said friction-bearings, thereby allowing considerable variation in the diameter of said friction-bearings.

Having now described my invention, what I claim as new, and desire to secure by Letters Patent, is—

1. A hoisting-machine provided with a lifting-chain wheel furnished with one or more spur-wheels, in combination with a pinion to rotate said chain-wheel, a shaft to rotate said pinion having journals of larger diameter than the said pinion, substantially as and for the purpose specified.

2. A hoisting-machine provided with a lifting-chain wheel furnished with one or more spur-wheels, in combination with a pivoted frame to support said chain-wheel, a pinion to rotate said chain-wheel, a frame to support said pinion, a shaft to rotate said pinion having journals of larger diameter than the said pinion, and adapted to pivot said frames together, substantially as and for the purpose specified.

3. A hoisting-machine provided with a lifting-chain wheel furnished with one or more spur-wheels, in combination with a pivoted frame to support said chain-wheel, a pinion to rotate said chain-wheel, a frame to support said pinion, a shaft to rotate said pinion having journals of larger diameter than the said pinion and adapted to pivot said frames together, and a hand-chain wheel and chain to rotate said shaft, substantially as and for the purpose specified.

4. A hoisting-machine provided with a lifting-chain wheel furnished with one or more spur-wheels, in combination with a pivoted frame to support said chain-wheel, a pinion to rotate said chain-wheel, a frame to support said pinion, a shaft to rotate said pinion, having journals of larger diameter than the said pinion and adapted to pivot said frames together, and a hand-chain wheel and chain to rotate said shaft, and a guide to prevent the hand-chain from becoming displaced from said hand-chain wheel, substantially as and for the purpose specified.

5. A hoisting-machine provided with a lifting-chain wheel furnished with one or more spur-wheels, in combination with a pivoted frame to support said chain-wheel, a pinion to rotate said chain-wheel, a frame to support said pinion, a shaft to rotate said pinion; hav-

ing journals of larger diameter than the said pinion and adapted to pivot said frames together, a lifting-chain, and a guide which follows the axis of the lifting-chain wheel to prevent the displacement of the chain therefrom, substantially as and for the purpose specified.

6. A hoisting-machine provided with a lifting-chain wheel furnished with one or more spur-wheels, in combination with a pivoted frame to support said chain-wheel, a pinion to rotate said chain-wheel, a frame to support said pinion, a shaft to rotate said pinion, having journals of larger diameter than the said pinion and adapted to pivot said frames together, and a hand-chain wheel and chain to rotate said shaft, and a guide to prevent the hand-chain from becoming displaced from said hand-chain wheel, a lifting-chain, and a guide which follows the axis of the lifting-chain wheel to prevent the displacement of the chain therefrom, substantially as and for the purpose specified.

7. The combination of frame-plates A and F, shaft B, lifting-chain wheel C, having spur-wheels D, pinion K, shaft J, having journals I of large diameter, chain-wheel L, chain R, and chain P, substantially as and for the purpose specified.

8. The combination of frame-plates A and F, shaft B, lifting-chain wheel C, having spur-wheels D, pinion K, shaft J, having journals I of large diameter, chain-wheel L, guide N, secured to frame-plates F, chain R, and chain P, substantially as and for the purpose specified.

9. The combination of frame-plates A and F, shaft B, lifting-chain wheel C, having spur-wheels D, guide M, pinion K, shaft J, having journals I of large diameter, chain-wheel L, chain R, and chain P, substantially as and for the purpose specified.

10. In a hoisting-machine, a lifting-chain wheel or drum and its chain, in combination with means to rotate said chain-wheel, a friction-bearing independent of said chain-wheel, and gearing to rotate said bearing by the rotation of the chain-wheel, the whole being so constructed as to bring the weight of the load supported by the lifting-chain upon said friction-bearing to prevent running down of the machine, substantially as and for the purpose specified.

In testimony of which invention I hereunto set my hand.

ROBERT REID.
